United States Patent Office

Des. 198,569
Patented July 7, 1964

198,569

BOOK END

Richard Schwarz, Livingston, N.J., assignor to Bro-Dart
Industries, Inc., Newark, N.J., a corporation of New York

Filed Nov. 12, 1963, Ser. No. 77,372

Term of patent 14 years

(Cl. D33—3)

FIG. 3

FIG. 1

FIG. 4

FIG. 1 is a rear perspective view of a book end showing my design;

FIG. 2 is a front and bottom perspective view thereof;

FIG. 3 is a side elevational view; and

FIG. 4 is a horizontal cross-sectional view taken on line 4—4 of FIG. 3.

I claim:

The ornamental design for a book end, substantially as shown.
